BLACK-OUT LIGHT SHADE AND PROTECTOR

Lester Wheeler Hughes, Newport, R. I.

Application January 7, 1942, Serial No. 425,924

3 Claims. (Cl. 240—108)

The invention relates to improvements in light protection and visibility for industrial and domestic use.

In the drawing, wherein like numerals refer to like parts throughout—

Figure 1 is a side elevational view.

Figure 2 is a top plan view.

Figure 3 is a transverse sectional view taken substantially on a line 3—3 of Figure 1.

Figure 4 is a fragmentary side elevational view showing the guide block for the upper end of the opaque shield, and

Figure 5 is a fragmentary side elevational view showing the catch for securing the collar in position to the bulb.

Referring now to the drawing in detail, the numeral 5 designates a split collar adapted for securing the position on a lamp socket, immediately above the lamp, the collar being composed of a pair of sections 6 and 7 having eyes 8 and 9 at one end overlying each other and through which a hinge pin 10 is inserted to hingedly connect the sections 6 and 7 in position.

Secured to the inner surface of the section 7 is a split spring ring 11 adapted for clamping engagement with the lamp socket (not shown), the split ring 11 being secured to the section 7 of the collar by a rivet 12.

The free ends of the sections 6 and 7 are disposed in overlapping relation as shown in Figure 2 of the drawing, one of the overlapping ends having a slot 13 formed therein and the other overlapping end of the section of the collar having a pin 14 journaled therein provided with a head 15 at its inner end adapted to be withdrawn through the slot 13 when the head is aligned therewith and the head 15 is adapted to bear against the split ring 11 to clamp the same in engagement with the lamp socket, upon a turning movement of the pin 14. The pin 14 is formed with a non-circular recess 16 to receive a tool for manipulating the head 15 into and out of its locking position.

The sections 6 and 7 of the collar are preferably constructed of plastic material and projecting from the lower edge of the section 6 is a transparent shield 17 while projecting from the lower edge of the section 7 of the collar is an opaque shield 18.

The shields 17 and 18 are of segmental form with their edges in overlapping relation as shown in Figure 3 of the drawing and of a shape substantially similar to that of an electric light bulb positioned therein so that the shield segments 17 and 18 combine to enclose the bulb.

Projecting from the section 6 of the collar adjacent its pivoted end is a stud 19 projecting through a slot 20 formed in an annular segment 21 formed at the upper end of a shield segment

22 of opaque material, the segment 22 is secured in adjusted position by a nut 23 threaded on the stud 19.

The bottom of the segment 17 is formed with a threaded stud 24 on which the lower end of the shield 22 is pivoted, the shield being secured in adjusted position by a nut 25 threaded on the stud 24.

In the operation of the device the shield segments 17 and 18 are secured in position about a bulb, rays of light from the bulb being excluded at one side thereof by reason of the opaque shield segment 18 while light may be projected from the opposite side of the bulb through the translucent shield 17.

The shield 22 may be moved into a position for covering or uncovering the shield segment 17 so that rays of light may also be concealed therefrom and the entire bulb covered by the opaque segments 18 and 22.

It is believed the details of construction, operation and manner of use of the device will be readily understood from the foregoing without further detailed explanation.

Having described the invention, what is claimed as new is:

1. A lamp shield comprising a pair of lamp enclosing segments, one segment being transparent and the other segment being opaque, a sectional collar carried by the segments for securing the segments on the lamp, a second opaque segment, and means for slidably securing the last-named segment on one section of the collar in covering position with respect to the transparent segment.

2. A lamp shield comprising a pair of lamp enclosing segments, one segment being transparent and the other segment being opaque, a sectional collar carried by the segments for securing the segments on the lamp, a second opaque segment, and means for slidably attaching the last-named segment to the section of the collar of the transparent segment for movement of the former into and out of covering position with respect to the latter.

3. A lamp shield comprising a split collar adapted for embracing a lamp socket, a split spring ring carried by the collar and adapted for clamping to the socket, means carried by the collar for securing the split sections thereof together, a shield carried by each section of the collar and cooperating to enclose a lamp mounted in the socket, one shield being opaque and the other shield being transparent, a second opaque shield partly enclosing said first-named shields, and means for adjustably securing said last-named shield on one of the first-named shields.

LESTER WHEELER HUGHES.
